UNITED STATES PATENT OFFICE.

SIMON LAKE, OF BERLIN, GERMANY.

TORPEDO-BOAT.

No. 876,564.

Specification of Letters Patent.

Patented Jan. 14, 1908.

Application filed March 22, 1907. Serial No. 363,941.

To all whom it may concern:

Be it known that I, SIMON LAKE, a citizen of the United States, at present residing at 23 Friedrich Wilhelmstrasse, Berlin, Germany, have invented a certain new and useful Improvement in Torpedo-Boats, of which the following is a full, clear, and exact description.

The object of this invention is to provide a 10 torpedo boat with loading and storage tubes for holding spare torpedoes, by and through which tubes the torpedoes are loaded into the firing tubes, and which are also employed to hold spare torpedoes in position to be readily inserted into the firing tubes after the 15 initial discharge of the torpedoes in the said firing tubes, said loading and storage tubes being loaded from above and being so arranged relatively to the firing or discharge 20 tubes that the torpedoes may be wholly or partially withdrawn from within the firing or storage tubes for the purpose of inspection or recharging, as is necessary before being discharged, especially should the torpedoes 25 have been held in the tubes for any considerable length of time, means being provided for closing the ends of the tubes, and additional means operable from within the vessel for controlling the outboard caps or sea caps 30 of the firing or discharge tubes.

The invention also has for its object a peculiar construction of the loading, storage and firing tubes, as well as other details, as will be fully set forth in the following specification and then pointed out in the claims.

In the accompanying drawings, illustrating the invention, in the several figures of which like parts are similarly designated, Figure 1 is a diagrammatic sectional elevation of a submersible torpedo boat, showing the location of my improved arrangement of firing tubes and storage and loading tubes. Fig. 2 is a diagrammatic plan view of the same illustrating the location of the loading 45 hatches. Fig. 3 is an enlarged detail horizontal section drawn on the line 3—3 of Fig. 4, one of the firing tubes and loading tubes being shown in elevation. Fig. 4 is a sectional elevation drawn on the irregular line 50 4—4 of Fig. 3. Fig. 5 is a longitudinal section of one of the firing tubes and Fig. 6 is a cross-section of the same. Fig. 7 is an enlarged cross-section drawn on the line 7—7 of Fig. 3, and Fig. 8 is a similar view on the line 55 8—8 of Fig. 3. Fig. 9 is a detail cross-section drawn on the line 9—9 of Fig. 3. Fig.

10 is an enlarged detail section showing a slight modification in construction of the strips arranged in the storage tubes. Fig. 11 is an enlarged detail section of the strips 60 used in the firing tubes and showing the manner of securing them in position.

A designates the hull of a submersible torpedo boat, having an upper deck or superstructure B, the side walls C, of which are secured to the hull in any suitable manner and extend from the hull in a vertical line substantially tangential therewith.

D designates the conning tower, E the propellers, and F the rudder.

The superstructure is arranged some distance above the top of the circular hull of the vessel and in the space thus formed, fore and aft, are the torpedo firing tubes G and G', respectively, whose inner ends extend into 75 hatches H and H', and having hatch holes H² and H³, respectively, communicating therewith through the superstructure.

Each firing tube is supported in position in any suitable manner and each is closed by a 80 sea-cap I, which is hingedly connected to the outer end of the tube. To these hinged connections are connected crank arms I', and to these crank arms are connected links I² whose opposite ends are connected to cranks 85 I³, held upon short vertical shafts I⁴, journaled in and projecting through stuffing boxes I⁵, secured to the top of the hull. The lower end of each shaft is provided with a worm wheel I⁶, each engaged by a worm J, 90 held upon the outer end of shafts J', J', extending longitudinally within the vessel, and which have their inner ends arranged near the inner ends of the firing tubes and provided with hand wheels J², by which the 95 shafts are operated to open and close the sea-caps. Where the shafts extend through the bulkheads of the vessel, I surround them with stuffing boxes to prevent ingress of water from one compartment to another should 100 either compartment be injured and spring a leak.

The torpedo firing tubes are constructed of sheet metal bent into tubular form and the meeting ends welded together to form a seam- 105 less tube.

Within each firing tube is securely fastened a skeleton frame forming a guide for the torpedo, said frame being constructed and arranged as follows: In the bottom of each 110 tube are two longitudinal strips K, K that extend nearly the entire length of the tube

and are spaced slightly apart to provide a 5 guide or race-way K', into which fits and slides the guide piece of the torpedo. Upon the sides of the tube at diametrically opposite 10 site points, and in the horizontal plane of the axis of the tube, are guide strips K², and in the apex of the tube in vertical alinement with the axis is a guide strip K³, all of which are connected at intervals by circular bands 15 K⁴, which extend circumferentially from the strips K, K and connect each of the remaining strips. (See Figs. 3, 5, 6 and 11).

The strips and bands are secured to the 20 tube by screws or rivets whose heads are countersunk in the strips and bands and their outer ends are projected through the tube and headed to prevent accidental displacement. The manner of securing the bands is best illustrated in Fig. 11 of the 25 drawings, and I have purposely omitted showing the fastenings in the remaining figures on account of the scale of the drawing.

After the tubes are thus constructed they 30 are placed in a lathe and the strips are cored or milled to provide a perfectly straight and even diameter throughout the length of the tube, which diameter is, of course, of a size to snugly fit a torpedo. It will be readily seen by this construction the tubes are made 35 much cheaper than those now used, and further they present much less frictional surface to the torpedoes, and also by the use of the strips it is unnecessary to finish the interior of the tubes, as no part of the torpedo comes into 40 contact therewith. As the bands connecting the strips of the firing tubes snugly fit the torpedoes, the discharge of the latter is accomplished in the same manner as if the tubes snugly fit the sides thereof. It will also be seen that the tubes will not be incapacitated through being dented or similarly injured as may happen in various ways.

Held in a space above the top of the hull, and in direct alinement with the aft torpedo 45 tubes are the storage and loading tubes L, each of which is constructed with a vertical extension L', open at its upper end and which extends through the superstructure B of the vessel.

The extensions are formed by the side 50 plates L² extending tangentially from the circular body portion of the tubes and connected at their ends by end plates L³ and L⁴, which are also secured to the circular body 55 portion of the tube. The ends L³ are preferably arranged upon an angle to provide an upwardly tapering throat which facilitates the insertion of the torpedoes in the tubes L, as illustrated in Fig. 4 of the drawings.

The opening of the extension of each tube 60 is closed by a hatch plate L⁵, which is bolted down to the superstructure. Each of the said tubes is also provided with guide strips L⁶, held in the bottom and upon the sides of 65 the tube. In practice I propose to make

these strips of wood, held in dove-tailed grooved metal strips L⁷, as shown in Fig. 10 of the drawing.

In the fore part of the space formed by the superstructure and in longitudinal alinement with the storage and loading tubes L, and the fore and aft firing tubes, are storage tubes M, having guide strips similar to those of the tubes L. The inner ends of each storage tube M projects into the conning tower and is closed by a cap M', preferably screwed in place, and which prevent ingress of water to the conning tower, should a leakage occur either through the hatches H and H', or the hatch covering the opening 80 of the loading tubes.

As shown in Fig. 4 of the drawings, the torpedoes are first lowered into each of the loading and storage tubes L through the openings L', from which they are first pushed 85 forwardly through the tubes into the tubes M, and thence into the firing tubes in the fore part of the vessel. Other torpedoes are then lowered and moved forwardly into the storage tubes M, where they are allowed 90 to remain. Other torpedoes are then lowered and moved rearwardly into the aft firing tubes, and finally the last torpedoes are lowered into and allowed to remain in the loading and storage tubes. It will thus 95 be seen that this operation is exceedingly simple and may be accomplished in very little time.

By the arrangement of the loading and storage tubes, a torpedo may be readily withdrawn from its firing tube for the purpose 100 of inspection, or recharging. Thus, the torpedoes in the aft tubes are examined in the rear hatch by first withdrawing the torpedoes in the loading and storage tubes into 105 the conning tower, and then by opening the inner caps of the aft tubes, the torpedoes may be withdrawn and their rear ends inserted into the loading and storage tubes and examined as they are moved forwardly 110 into the tubes, after which they are replaced and the torpedoes previously withdrawn from the storage tubes into the conning tower are replaced, having in the meantime been examined in the conning tower. The identical 115 operation is also performed with respect to torpedoes carried in the forward tubes, as that described with respect to the torpedoes in the aft firing and storage tubes. It will also be seen that when a torpedo has been 120 discharged another may be readily inserted in its place from the storage tube, held in longitudinal alinement with the tube from which the torpedo has been discharged.

While I have shown a construction and 125 arrangement of firing and storage tubes, I have not thought it necessary to show in detail the mechanism for firing the torpedoes, nor have I shown in detail the manner of securing the tubes in position, as any suit- 130

able means may be employed, and therefore do not make claim to such details, but

What I do claim and desire to secure by Letters Patent is:

5. 1. A torpedo boat, provided with a firing tube, a hatch into which it opens, a storage tube also opening into said hatch and alined with the firing tube and having a loading hatch, and means for closing the said hatch.
10. 2. A torpedo boat, provided with a firing tube, a storage tube alined with the firing tube and having a vertical extension projecting through the vessel to provide a loading hatch, and means for closing the hatch.
15. 3. A torpedo boat, having a superstructure, and torpedo firing tubes held in the space formed by the superstructure and top of the hull of the vessel, a storage tube alined with the firing tube and having an extension which projects through the said superstructure to provide a loading hatch and means for closing the hatch.
20. 4. A torpedo boat, having a superstructure, and torpedo firing tubes held in the space formed by the superstructure and hull of the vessel, a storage tube alined with the firing tubes, combined loading and storage tubes also in alinement with the firing tubes and each having an extension which projects through the superstructure to provide a loading hatch, and a cover for the said hatch.
25. 5. A torpedo boat, having a superstructure, and torpedo tubes held in the space formed by the superstructure and hull of the vessel and fore and aft of the said vessel, storage tubes alined with the fore firing tubes, combined loading and storage tubes alined with all of the aforementioned tubes and adjacent to the aft firing tubes, the said combined loading and storage tubes having extensions which project through the superstructure to provide loading hatches through which the torpedoes are lowered and passed to the remaining tubes.
30. 6. A torpedo boat, having a superstructure, and torpedo firing tubes held in the space formed by the said superstructure and the hull of the vessel, outboard caps for closing the outer ends of the tubes hingedly held adjacent to the said tubes, crank arms connected to said caps, a shaft journaled adjacent to each firing tube and having a crank at one end, a link connecting the crank with the crank carried by the cap, the inner end of each shaft projecting through the hull of the vessel and having a worm wheel at its inner end, shafts journaled within the vessel and having worms which engage the worm wheels and having their opposite ends provided with handles for revolving the shafts, hatches formed in the vessel into which the inner ends of the tubes and shafts project, storage tubes alined with the firing tubes, each having one end projecting into the
35. hatches into which the firing tubes project and caps for closing the other ends of the storage tubes.
40. 7. A torpedo boat having a superstructure, fore and aft firing tubes arranged in the space formed by the superstructure and the hull of the vessel, hatches communicating with the said space and into which the inner ends of the firing tubes extend, storage tubes alined with the firing tubes and having their discharge ends extending into the hatches into which the loading ends of the firing tubes project, one set of the said storage tubes having extensions projecting through the superstructure and through which the torpedoes are loaded into all of the storage tubes and thence into the firing tubes, covers for closing the extensions, caps for closing the inner ends of the storage tubes, and means for closing the ends of the firing tubes.
45. 8. The combination with a torpedo boat having a superstructure, and hatches communicating with the space formed by the superstructure and the hull of the vessel, of torpedo firing tubes having their inner ends extending into the hatches, and storage and loading tubes alined with the firing tubes and each having one end extending into one of the hatches, means for closing the other ends of the loading and storage tubes, means for closing the inner ends of the firing tubes, outboard caps closing the outer ends of the firing tubes and means operable from within the vessel for controlling the position of the said outboard caps.
50. 9. In a torpedo boat, the combination with a torpedo firing tube, of a storage tube held in longitudinal alinement with the said firing tube but separated therefrom, thereby providing a space for the inspection of a torpedo as it is passed to or from the said firing tube.
55. 10. In a torpedo boat, the combination with a torpedo firing tube, of a storage tube held in longitudinal alinement with the firing tube for holding a reserved torpedo, a hatch interposed between the adjacent ends of these tubes, means for closing the ends of the firing tube and means for closing one end of the storage tube.
60. 11. In a torpedo boat, the combination with torpedo firing tubes and means for closing the ends thereof, of storage tubes held in longitudinal alinement with the firing tubes and spaced therefrom so as to permit total or partial withdrawal of the torpedo for inspection, one of the said storage tubes having an extension which projects through the vessel and means for closing the said extension, and means for closing the inner ends of the said tubes.
65. 12. In a torpedo boat, the combination with a torpedo firing tube having a removable cap and means arranged within the vessel for opening and closing the said cap, of a

storage tube arranged in longitudinal alinement with the firing tube and spaced therefrom so as to permit total or partial withdrawal of the torpedo for inspection, an 5 extension formed upon the storage tube which extends through the vessel to permit the insertion of torpedoes into the firing tube without necessitating the opening of the outboard cap, and means for closing the opening 10 of the said extension.

13. In a torpedo boat, the combination with torpedo firing tubes arranged fore and aft of the vessel, of a storage tube arranged in longitudinal alinement with the firing tube 15 in the fore part of the vessel and spaced from the said firing tube so as to permit total or partial withdrawal of the torpedo for inspection, a loading and storage tube arranged in longitudinal alinement with the aft firing 20 tube and similarly spaced therefrom for a like purpose, an extension formed upon the said loading and storage tube through which torpedoes are passed to the said tubes, and means for closing the opening of the extension. 25

14. In a torpedo boat, having a conning tower, a superstructure and hatches communicating with the space formed by the superstructure, the combination with torpedo firing tubes held in the said space and having their inner ends extending into the hatches, of storage tubes also held in said space and each having one end extending into the said hatches and their opposite 35 ends projecting into the conning tower, and means for closing the said ends within the tower.

15. In a torpedo boat, having a conning tower, a superstructure and hatches arranged in the hull in the fore and aft part 40 of the boat and communicating with the space between the top of the hull and superstructure, the combination with torpedo firing tubes, held in the space and at each 45 end of the vessel and having their inner ends extending into the said hatches, of storage tubes held in the fore part of the vessel and having their forward ends extending into the hatch and their rear ends 50 extending into the conning tower, a cap adapted to fit upon the inner end of each tube, loading and storage tubes arranged in the said space and in advance of the aft firing tubes, one end of the said loading and 55 storage tubes being extended into the rear hatch and their forward ends into the conning tower and having caps to fit upon the said forward ends, an extension formed upon each tube and projecting through the deck 60 of the superstructure and a cover for each extended end, outboard caps for closing the firing tubes and means operable from within the vessel for opening and closing the said caps. 65

16. A torpedo boat, having a conning

tower, a superstructure and hatches communicating with the space formed by the superstructure and the top of the vessel, torpedo firing tubes located in the said space fore and aft of the vessel, the inner 70 ends of the said tubes extending into the hatch adjacent to the tubes and having removable caps, an outboard cap pivotally held to each tube and means within the vessel for opening and closing the said outboard caps, 75 storage tubes held in the said space in the fore part of the vessel and in longitudinal alinement with the firing tubes, and having their forward ends projecting into the hatch in the forward part of the vessel and their 80 rear ends extending into the conning tower, caps for closing the said ends, storage tubes also arranged in the said space in the aft part of the vessel and having their rear ends projecting into the hatch in the rear part of 85 the vessel and their forward ends into the conning tower, caps for closing the said forward ends, an extension formed upon each of said storage tubes and projecting through the said superstructure thereby providing an 90 opening through which torpedoes are inserted into the tubes, and means for closing the open ends of the extensions.

17. In a torpedo boat, the combination with torpedo firing tubes, of guide strips 95 held in the tubes, storage tubes held in longitudinal alinement with the said firing tubes and having guide strips arranged therein, one of the said tubes having an extension providing an opening through which torpedoes are loaded into the tubes, and means for closing the opening of the said extension. 100

18. A torpedo firing tube, for torpedo boats, comprising a tubular body portion, guide strips arranged therein throughout 105 the length of the tube and bands connecting the said strips at intervals throughout the length of the strips.

19. A torpedo firing tube, comprising a tubular body portion having guide strips 110 arranged therein, said strips being arranged at diametrically opposite points within the tube, bands connecting the strips at intervals throughout the length thereof, and means for securing the strips to the tube. 115

20. A torpedo firing tube, constructed of a sheet of metal bent into tubular form and the ends welded to provide a seamless tube, guide strips held within the tube at the bottom, sides and top, the said bottom strips 120 being slightly spaced apart to provide a guide or race-way for the guide piece of the torpedo, and all of the strips provided with a smooth surface.

In testimony whereof I have hereunto set 125 my hand this 9th day of March A. D. 1907.

SIMON LAKE.

Witnesses:

M. D. BLONDEL,
HENRY HASPER.

It is hereby certified that in Letters Patent No. 876,564, granted January 14, 1908, upon the application of Simon Lake, of Berlin, Germany, for an improvement in "Torpedo-Boats," errors appear in the printed specification requiring correction, as follows: In line 62, page 2, the word "tot" should read *to*, and in line 129, page 3, the word *outboard* should be inserted before the word "cap"; and that the said Letters Patent should be read with these corrections therein that the same may conform to the record of the case in the Patent Office.

Signed and sealed this 28th day of January, A. D., 1908.

[SEAL.]

C. C. BILLINGS,
Acting Commissioner of Patents.
